ABSTRACT OF THE DISCLOSURE

A slub catcher having a passage through which yarn is drawn as it is wound onto a package, the passage being of the kind designed to trap long slubs and to permit short slubs to pass through.

Background of the invention

Slub catchers have been used for a long time, a common type embodying a narrow passage or slot wide enough at its entrance end to admit the yarn and narrowing down toward its exit end sufficiently so that unacceptable enlargements (slubs) in the yarn are intercepted. Numerous slub catching devices have been designed to enable selectively eliminating slubs depending upon their size and length, the purpose being to remove the large long slubs but to permit the smaller and shorter ones to pass through. However, such devices as are available cannot be adjusted with sufficient precision to enable such discrimination. It is the principal purpose of this invention to provide a method and apparatus for catching slubs which will trap long and large slubs while permitting short and small slubs to pass through; to provide an apparatus for this purpose which does not require precise adjustment; and to provide an apparatus which is effective for yarns of substantially all kinds and under the high-speed winding operations now used.

Summary

As herein illustrated, the apparatus comprises rigid parts supported with portions of their surfaces in spaced confronting relation so as to define a passage or slot coinciding with the path of travel of the yarn being wound and diminishing in cross-section from a size large enough to receive the yarn at its entrance end to a size no smaller than the allowable reduction in diameter of the yarn within approximately an inch of travel of the yarn along the passage. Specifically a reduction of .003 of an inch per inch of length of passage, for example, from an entrance diameter of .010 to an exit diameter of .007 inch per inch of length. As thus dimensioned short and small slubs are progressively reduced in size by the converging surfaces so as to pass through the slot while the large slubs, because of their greater mass, cannot be reduced sufficiently within this length to pass. The apparatus functions to progressively reduce the diameter of the yarn at any given point at a rate such as to prevent surge and this is accomplished by displacing the yarn radially toward its longitudinal axis and any of its projecting fibers rearwardly relative to the direction of movement of the yarn at a rate less than the inertial resistance to such

2

radial and rearward displacement of the fibers making up the yarn. Preferably the yarn is reduced in diameter from its uncompressed size to no less than its allowable reduction in size in one inch of travel by reducing its size at the rate of .003 inch per inch of travel.

5 The invention will now be described in greater detail with reference to the accompanying drawings wherein:

FIG. 1 is a left-hand view, partly in vertical section, of a portion of a winding machine showing in elevation the head portion of a travelling winding unit;

10 FIG. 2 is a front elevation of the head of the machine showing the slub catching device of this invention mounted thereon;

FIG. 3 is a horizontal section taken on the line 3—3 of FIG. 2;

FIG. 4 is a section taken on the line 4—4 of FIG. 2;

FIG. 5 is a section taken on the line 5—5 of FIG. 2;

15 FIG. 6 is an enlarged fragmentary section of a yarn passage in which surging takes place due to too rapid reduction in too short a distance; and

20 FIG. 7 is an enlarged fragmentary section of a yarn passage wherein smooth flow of the yarn through the passage is achieved by a gradual rate of reduction of an enlargement in the yarn.

25 The invention as herein illustrated is applied to a travelling spindle winding machine such as illustrated in Patent No. 2,623,265, comprising a large number of travelling winding units adapted to wind yarn during their travel in a closed path around the machine. As shown in FIG. 1, the machine has a head portion 10 supported for movement along a track 12 parallel to the axis of a drive roll 14 which has contact with the peripheral surface of the winding package P. The yarn Y being wound on the package is drawn from a suitable source across an apron 16 and is traversed as it is wound onto the package by a reciprocating thread guide 18, the foregoing components being conventional in machines of this kind. It is customary to provide transversely spaced guide rods 20—20 to center the yarn in its course and these are attached to the apron extending forwardly therefrom and flaring laterally outward to receive the yarn. The slub catcher 22, as herein illustrated, is mounted on the apron between the upper and lower extremities of the guide rods and comprises a pair of rigid elongate blocks 24, 26 mounted on the apron, the block 26 being disposed in an upright position and removably fixed to the apron by means of screws 28. The block 24 is mounted next to the block 26 in a similar upright position with its upper and lower ends supported between vertically spaced bearing blocks 30, 32

35 so that it can slide forwardly and rearwardly relative to the block 26. A spring-pressed plunger 34 mounted in the end of an arm 36 pivotally supported on the apron by engagement with the block 24 normally holds the latter in a rearwardly displaced position. The bearing blocks 30, 32 are fastened to the face of the apron at the upper and lower ends of the blocks 24, 26 and support the upper and lower ends of the rods 20.

40 The block 26 has a uniformly flat surface 42 confronting the block 24 and the block 24 has a correspondingly uniformly flat surface 44 confronting the block 26 except at the forward part which is recessed to provide a surface 46 spaced from that of the block 26, the surface 46 being

flat and parallel to the surface 42 of the block 26 in a direction transversely but inclined with reference to the longitudinal surface of the block 26 as will appear hereinafter. The flat spaced surfaces 42, 46 of the blocks 26 and 24 constitute a clear passage or slot 48 through which the yarn passes on its way to the reciprocating guide 18 which traverses it as it is wound onto the package. The block 24 is slidably supported relative to the block 26 and yieldably held thereagainst in this position to enable clearing the slab catcher in the event that it becomes choked with an accumulation of fibers stripped from the surface of the yarn and also to minimize the stripping of fibers.

In my prior slab catchers the blocks 24 and 26 are relatively short in the direction of travel of the yarn, for example, in the order of $\frac{1}{4}$ inch and at a relatively high linear speed of winding it is virtually impossible to adjust the spacing of the blocks to intercept long slabs without also catching the short slabs. The reason for this is that the yarn cannot be condensed fast enough in the relatively short length of its travel to flow smoothly through the passage without surging. Such surging is diagrammatically illustrated in FIG. 6 in which the converging portion of the passage is approximately $\frac{1}{4}$ inch in length and is caused in part by inertial resistance of the yarn to radial compression, that is, displacement at right angles to its longitudinal axis and in part by resistance of the individual fibers projecting outwardly from the yarn to rearward bending into parallelism with the axis of the yarn. Such inertial resistance to displacement can be substantially dissipated without sacrifice in winding speed by effecting condensation at a slower rate. This is achieved herein by inclining the portion of the face 46 situated between the lines X—X' approximately one inch in length relative to the face 44 so that they converge from their entrance end at X to their exit end X' at a rate of approximately .003 inch per inch of length, the converging character of the passage being clearly illustrated in elevation in FIG. 2 between the lines X—X' and in section in FIGS. 4 and 5. The surfaces 44, 46 throughout the remainder of the passage, that is from X'—X'' is of uniform width and will permit passage of the yarn condensed in the part X—X', but will intercept any uncondensed enlargement therein. This portion X'—X'' of the passage corresponds substantially in width to the maximum allowable condensation of the yarn possible without breakage. FIG. 7 diagrammatically illustrates the passage shown in FIGS. 2, 4 and 5 wherein the sides converge at a rate of .003 inch per inch of length (between the lines X—X') and shows the smooth flow of a relatively small enlargement in the yarn through the passage. The elongation of the slot or passage at its entrance end with its gradual taper provides for effectively reducing relatively short and small slabs slow enough to avoid surging and hence to compress them sufficiently to pass freely into and through the exit end of the passage, that is the portion X'—X''. Because the long slabs contain considerably more bulk than the short slabs the lengthening of the portion X—X' of the passage does not suffice to effect their compression soon enough to avoid surging and breakage.

The device as described affords a method of discriminating between large long slabs and small short slabs and so enables removal of objectionable slabs while permitting the unobjectionable slabs to pass through, the method being characterized in that it is effected by subjecting the yarn to gradual condensation and any slabs present therein at a rate such as to avoid surge resulting from inertial resistance of the yarn to condensation at the linear speed it is travelling and inertial resistance of the fibers of which the yarn is comprised to being displaced rearwardly with respect to the direction of movement of the yarn.

I claim:

1. Apparatus for catching slabs comprising rigid parts having spaced confronting surfaces defining a yarn passage through which the yarn is adapted to be drawn as it

is wound onto a package, said passage having aligned first and second portions characterized in that the first portion has surfaces which converge in the direction of travel of the yarn from a width slightly greater than the uncompressed diameter of the yarn at its entrance end to a terminal width not substantially less than the allowable compression of the yarn at the exit end within a distance such that surging is negligible, and said second portion has surfaces which are substantially parallel and correspond substantially in width to the terminal width of the first portion.

2. Apparatus according to claim 1, wherein said surfaces of the first portion converge at a rate which is substantially less than the inertial resistance to radial condensation of the yarn relative to its longitudinal axis.

3. Apparatus according to claim 1, wherein said surfaces of the first portion converge at a rate which is substantially less than the inertial resistance to bending of the fibers of the yarn relative to the longitudinal axis of the yarn.

4. Apparatus according to claim 1, wherein said surfaces of the first portion converge at a rate of .003 inch per inch of length.

5. Apparatus according to claim 1, wherein said surfaces of said first portion converge from an entrance width of .010 to an exit width of .007 inch in one inch of length.

6. The method of catching slabs in the winding of yarn comprising moving the yarn at a predetermined linear speed, applying pressure at right angles to the axis of the yarn which progressively condenses enlargements therein from a diameter slightly greater than the maximum diameter of the yarn to a diameter not less than the minimum allowable condensation of the yarn at a rate less than produces surging at said linear rate of travel, and interrupting such enlargements as fail to be compressed to said maximum diameter of the yarn.

7. The method of catching slabs in the winding of yarn of a predetermined diameter, comprising pulling the yarn as it is wound onto a suitable holder through a continuous yarn passage, the width of which diminishes at a rate such that enlargements of relatively short length are condensed without surging as they move through the yarn passage and at a predetermined point along the passage intercepting such enlargements as fail to be compressed to said predetermined diameter.

8. The method of catching slabs in the winding of yarn comprising pulling the yarn through a yarn passage which decreases in width from a width greater than that of the yarn and small enlargements therein, to a diameter not less than the allowable condensation of the yarn at a rate such that the rate of change in the diameter of the yarn takes place without surging, and intercepting such enlargements as fail to be compressed.

9. The method of catching slabs in the winding of yarn comprising pulling yarn having a diameter of approximately .010 inch through a yarn passage which diminishes in width from a width at its entrance end in the order of .010 inch to a width at the exit end of .007 inch within an inch of its length, and intercepting such enlargements as fail to be compressed to the diameter of the yarn at the exit end.

10. The method of catching slabs in the winding of yarn comprising pulling the yarn through a yarn passage that has a taper of .003 inch per inch of length to compress such enlargements in the yarn as are greater than its maximum diameter, and thereafter intercepting such other enlargements in the yarn as fail to be compressed to the aforesaid yarn diameter.

11. The method of catching slabs in the winding of yarn comprising moving the yarn linearly at a predetermined speed, subjecting the yarn during such linear movement to progressive compression at a rate less than the inertial resistance of the fibers of which the yarn is comprised to radial displacement with respect to the axis of

the yarn at said speed, and following such compression intercepting such enlargements as fail to be compressed to said yarn diameter.

12. The method of catching slubs in the winding of yarn of a predetermined diameter comprising moving the yarn linearly at a predetermined speed, subjecting the yarn to progressive compression at a rate less than the inertial resistance of the fibers of which the yarn is comprised to rearward displacement with respect to the direction of movement of the yarn into parallel relation with the axis of the yarn at said speed, and following such compression intercepting such enlargements as fail to be compressed to said yarn diameter.
